UNITED STATES PATENT OFFICE.

MONTGOMERY W. McCONKEY, OF CHICAGO, ILLINOIS, ASSIGNOR TO BENDIX BRAKE COMPANY, OF CHICAGO, ILLINOIS, A CORPORATION OF ILLINOIS.

BRAKE.

Application filed October 7, 1925. Serial No. 60,990.

This invention relates to brakes, and is illustrated as embodied in a three-shoe "Bendix" brake. An object of the invention is to provide greater simplicity of the end shoes, by forming the central shoe at its ends to overlap the end shoes. Preferably this is done by making the central shoe T-shaped in section at its center and providing it with spaced flanges at one or both ends to straddle the ends of the other shoes, as for example by making the ends of the central shoe of channel form.

In one desirable arrangement, the central shoe is made by securing back to back two L-section stampings, and spreading their radial flanges apart at both ends of the shoe to form the spaced flanges. I prefer to fasten a separate plate across each pair of spaced flanges to form a continuation of the friction face.

The above and other objects and features of the invention, including various novel combinations of parts and desirable particular constructions, will be apparent from the following description of one illustrative embodiment shown in the accompanying drawings, in which:

Fig. 1 is a side elevation of the shoes in assembled relation;

Fig. 2 is a section on the line 2—2 of Fig. 1, showing the connection between two of the shoes;

Fig. 3 is a section on the line 3—3 of Fig. 1, showing the same connection;

Fig. 4 is a section through the central shoe on the line 4—4 of Fig. 1; and

Fig. 5 is a section through the adjacent ends of two of the shoes on the line 5—5 of Fig. 1.

The brake shown in Fig. 1 includes generally a central shoe 10 anchored at 12, a servo end shoe 14, and a reverse end shoe 16. Shoes 14 and 16 are forced apart to apply the brake, against the resistance of return springs 18 and 20 by means such as a double cam 22.

The central shoe 10 is made up largely of two L-section stampings (Fig. 4) having oppositely-extending cylindrical flanges 24 carrying the brake lining, and radial webs 26 riveted or otherwise secured together, the flanges being arranged back to back.

At each end of the shoe 10, flanges or webs 26 are forked or spread apart to form

spaced parallel flanges straddling the end of one of the shoes 14 or 16. Flanges 24 on these spaced webs are depressed to receive a pair of plates 28, one at each end of the shoe, bridging the spaced webs and riveted or otherwise secured to flanges 24 to form continuations of the face of the shoe, thus forming a channel section at each end of the shoe.

At the unanchored (left) end of shoe 10, a pin 30 pivotally connects the end of shoe 14 to the flanges 26 between which it projects. Preferably pin 30 has a large enough head to engage slidably the backing plate of the brake, to position the shoe laterally. While shoe 16 may if desired be anchored directly on the backing plate, as illustrated and described in Dodge Patent No. 1,567,716, I prefer that it be pivotally connected to its pair of flanges 26 at the anchored (right) end of shoe 10 by a pin 32 which may, if desired, be identical and interchangeable with pin 30.

Flanges 26 at the right end of shoe 10 extend beyond their plate 28, to be pivoted upon the fixed anchor 12, which passes through a relatively large opening in shoe 16 so that it does not interfere with the movement of that shoe.

While one illustrative embodiment has been described in detail, it is not my intention to limit the scope of the invention to that particular embodiment, or otherwise than by the terms of the appended claims.

I claim:

1. A brake comprising, in combination, a central shoe T-shaped in section at its center and having spaced flanges at each end, and end shoes, each of which extends between the spaced flanges at one end of the central shoe, beyond the end of the friction face of the central shoe.

2. A brake comprising, in combination, a central shoe T-shaped in section at its center and having spaced flanges at each end, and end shoes, each of which extends between the spaced flanges at one end of the central shoe, together with two plates each bridging one set of spaced flanges at one end of the central shoe and forming a part of the face of the shoe.

3. A brake comprising, in combination, a central shoe T-shaped in section at its center and having spaced flanges at each end, and end shoes, each of which extends be-

tween the spaced flanges at one end of the central shoe beyond the end of the friction face of the central shoe, together with means for taking braking torque at one end of the central shoe.

4. A brake comprising, in combination, a central shoe T-shaped in section at its center and having spaced flanges at each end, and end shoes, each of which extends between the spaced flanges at one end of the central shoe, beyond the end of the friction face of the central shoe, together with means for taking braking torque at one end of the central shoe and means for connecting the end shoes to the central shoe.

5. A brake shoe channel-shaped at both ends and T-shaped in cross-section at its center.

6. A brake shoe channel-shaped at both ends and T-shaped in cross-section at its center, and having the side flanges of one channel-shaped end extended and provided with anchoring means.

7. A brake shoe made of pressed-metal parts, two of which are L-shaped in cross-section and secured together back to back with the radial parts in engagement at the center of the shoe and spread apart to form spaced parallel flanges at both ends of the shoe.

8. A brake shoe made of pressed-metal parts, two of which are L-shaped in cross-section and secured together back to back with the radial parts in engagement at the center of the shoe and spread apart to form spaced parallel flanges at both ends of the shoe, together with two plates bridging the flanges at the two ends of the shoe.

9. A brake comprising, in combination, a central shoe T-shaped in section in its central portion and having spaced flanges at least at one end, an end shoe projecting between said flanges at the end of the shoe beyond the end of the friction face of the shoe to overlap part of the shoe, means to take braking torque from the overlapped ends of the shoes, and another shoe connected to the opposite end of the central shoe and arranged to apply the central shoe.

10. A brake comprising, in combination, a central shoe T-shaped in section in its central portion and having spaced flanges at least at one end, an end shoe projecting between said flanges at the end of the shoe beyond the end of the friction face of the shoe and pivoted to said flanges of the shoe, and another shoe arranged at the opposite end of the central shoe, the two end shoes being arranged to be forced in opposite di-

rections to apply the brake, and at least one of the end shoes being arranged to apply the central shoe.

11. A brake comprising, in combination, a central shoe made up of pressed metal parts including two stiffening flanges secured together in the central part of the shoe to form a single stiffening web and spread apart to form spaced flanges at least at one end of the shoe, an end shoe projecting between said spaced flanges to overlap part of the central shoe, means for taking braking torque from the overlapped ends of the shoes, and another end shoe connected to the opposite end of the central shoe, the two end shoes being arranged to be forced in opposite directions to apply the brake.

12. A brake comprising, in combination, a central shoe made up of pressed metal parts including two stiffening flanges secured together in the central part of the shoe to form a single stiffening web and spread apart to form spaced flanges at least at one end of the shoe, an end shoe projecting between and pivoted to said spaced flanges to overlap part of the central shoe, and another end shoe arranged at the opposite end of the central shoe, the two end shoes being arranged to be forced in opposite directions to apply the brake.

13. A brake shoe having in its center a single stiffening web which is forked at both ends of the shoe to form spaced flanges for straddling the ends of adjacent shoes, together with means bridging the flanges at least at one end to form a channel-shaped portion.

14. A brake shoe having a curved friction face and a single stiffening web forked at one end of the shoe before the end of the friction face to straddle and be connected to the end of an adjacent shoe, and extending beyond the friction face and arranged to be pivoted on an anchor at the opposite end of the shoe.

15. A brake shoe having a curved friction face and a single stiffening web formed at one end of the shoe to be pivoted to the end of an adjacent shoe, and forked at the other end of the shoe before the end of the friction face and extended as a pair of spaced flanges projecting beyond the friction face and arranged to be pivoted upon an anchor and to straddle the end of another adjacent shoe.

In testimony whereof, I have hereunto signed my name.

MONTGOMERY W. McCONKEY.
